UNITED STATES PATENT OFFICE.

JOHN A. SECOR, OF BROOKLYN, NEW YORK.

ENGINE FOR MARINE PROPULSION.

SPECIFICATION forming part of Letters Patent No. 398,659, dated February 26, 1889.

Application filed November 3, 1888. Serial No. 289,918. (No model.)

To all whom it may concern:

Be it known that I, JOHN A. SECOR, of Brooklyn, in the county of Kings and State of New York, have invented a certain new and useful Improvement in Engines, of which the following is a specification.

My invention relates more particularly to engines employed for the propulsion of marine vessels; but it is not confined in this application to such engines.

I will describe an engine embodying my improvement in detail, and then point out the novel features in claims.

In the accompanying drawings, Figure 1 is a vertical longitudinal section (through the line $x x$ of Fig. 2) of an engine embodying my improvement and of a portion of a vessel containing such engine. Fig. 2 is a top or plan view of the engine, showing the arrangement of the exploding agency; and Fig. 3 is a longitudinal section of an injector.

Similar letters of reference designate corresponding parts in all the figures.

Referring by letter to the drawings, A designates the stern portion of a vessel, and A' indicates the rudder thereof.

B designates chambers, preferably of metal, arranged in the lower part of the stern portion of the vessel. These chambers may be of any required number, placed side by side and entirely independent of each other, excepting as to certain connections, hereinafter set forth. In the present example I have shown four chambers B, which for convenience are numbered 1 2 3 4, the operating mechanism, however, being similar in each. I will particularly describe but one. The chamber B is approximately rectangular in cross-section. The rear end extends or opens outward through the stern of the vessel, and the front end is bent or extended downward and opens through the bottom of the vessel. At the rear end the chamber has combined with it a valve, B', and at its forward end it has combined with it a similar valve, B². When it is desired that the vessel shall be propelled forward, the valve B² must be closed and the valve B' opened. The valves B' B² may be operated by any suitable mechanism. I have here shown the valves as fitted in a slideway, b', so that they may be adjusted vertically

therein. Part of this slideway is made in the form of a trunk extending above the chamber B. A threaded rod, b², extends upward from each valve B' B² through a suitable stuffing-box in the top wall of the trunk, where it is engaged by a tapped operating-wheel, b³. It is to be understood that these operating-rods may extend to any desirable location—say above deck of the vessel—and it is obvious that by means of the threaded rods the valves may be opened to any required extent.

I have shown at the forward extremity of the chamber B a gate, B³, which is hinged at its rear end to the chamber and connected at the forward end by a link, b⁵, with a screw-threaded rod, b⁴, that extends upward into the vessel through a stuffing-box, with which the chamber is provided. A nut or wheel, b⁵, is combined with the screw-rod, so that by rotating this nut the gate B³ may be lowered or raised to open or close the forward end of the chamber B. The forward portion of the chamber B is so bent or extended that in conjunction with the gate B³, when lowered at an angle to the vessel, it will direct the force produced by explosions within the chamber B properly to effect a rearward motion of the vessel. The gate B³, instead of being operated by the mechanism described, may be operated in any other desirable manner.

The valves B' B², to which I have already referred, are, as it will have been understood, intended to operate solely at the will of an attendant. The chamber B has also combined with it valves C' C², which are intended to act automatically. The valve C' will operate only when the valve B' is open, and the valve C² will operate only when the valve B² and gate B³ are open. The object of the valves C' C² is to permit of the force of an explosion within the chamber B to be exerted upon the water at either end of the chamber B, and yet to prevent the subsequent influx of water into the chamber. Therefore these valves C' C² open outward under the influence of the force produced within the chamber and close inward when acted upon by the force of the water outside the chamber. The frames for these valves are preferably made of metal, which have each two rectangular openings, and the frames fit at the edges in recesses in

the side walls and bottom of the chamber B, and the valves may be drawn upward into trunks by means of a screw-rod and nut, as before described. The valves are designed to 5 close the rectangular openings through the frames on the outer side, and the said valves are preferably composed of india-rubber, a sheet of leather arranged adjacent to that side of the rubber next the frame, a plate of 10 sheet-iron arranged against the leather, a block or piece of wood arranged adjacent to the other side of the rubber, and a plate of sheet-iron arranged against the outer side of the piece of wood. I have found that this 15 combination of material is of great importance in making the valves for my engine. The various parts may be secured together by means of screw-bolts and nuts, or otherwise.

F designates a receptacle containing hydro- 20 carbon, such, for instance, as kerosene. It is connected by a pipe, F', to the injector E.

The receptacle F is here shown as connected to a ceiling or other raised portion above the engine, and the pipe F' extends from the 25 lower portion of the receptacle to the injector E, and as being provided near the injector with a check-valve, f, which will open toward the injector E and chamber B, but will close in the reverse direction, so as to exclude from 30 the pipe F' and receptacle F any force or pressure of gases which may be generated in the chamber B.

I have described a receptacle for containing 35 a liquid fuel for producing combustion within the chamber; but it is to be understood that other fuel may be used, such, for instance, as coal-dust, fuel-gas, &c.

The injector E consists of a shell, e, a piece, e', fitted in one end of the shell e, which is 40 farthest from the pipe F', and a piece, e², fitted into the shell e. The piece e' is provided with two tapering openings, which are largest at the end of the piece and which at their smaller diameters meet and communicate. 45 The piece e² extends into one of the tapering cavities of the piece e', and itself has a tapering hole throughout its length. It will be seen that the diameter of the outer end of the piece e² is less than the smallest diameter of 50 the piece e'. The space between the piece e² and the tapering cavities of the piece e', into which it extends, communicates with the pipe F', leading from the hydrocarbon-receptacle F. The interior of the piece e² communicates 55 with the pipe D', leading to an opening into another of the chambers B. The pipe or conduit D' has an inwardly-opening check-valve, b⁶, within it near the injector. The force of 60 the compressed air will draw the hydrocarbon into the injector, and, owing to the peculiar construction of the piece e', will dash the hydrocarbon into a spray. In the form of a spray the hydrocarbon enters the chamber B with the compressed air.

65 Means whereby the hydrocarbon and the air within a chamber B may be exploded may be described as follows:

G designates a source of electricity, which may be a battery or a dynamo-electric machine.

G' shows wires extending from the poles of the generator to two electrodes, G² G³. These electrodes extend through the wall of the chamber B, and are adapted to contact with each other within said chamber. They are 70 insulated from the chamber and from each other. The electrode G³ is stationary. The electrode G² is, however, vertically movable, in order that its inner end may be made to contact with the electrode G³, which has its 75 end bent upward, or may be operated therefrom, as occasion may require. It is intended that normally the electrodes shall be in contact, and that they shall be separated at the proper times to produce sparks, whereby 80 air and hydrocarbon within the chamber B may be ignited.

H designates a cylinder having a small opening into the chamber B; and H' is a piston or plunger valve within the cylinder H, 90 from which extends a rod, h, through a spring-controlled cover, h', which is adapted to fit snugly within the upper aperture of the cylinder when the piston is allowed to fall by a vacuum in the chamber. A chain or cord, h², 95 is secured at one end to the rod h, and leads over suitable ways or pulleys to a connection with a movable electrode, G², in another chamber, for a purpose hereinafter explained.

The chamber B is provided with what I 100 term an "air-inlet," B⁴. This consists of a passage or conduit arranged above but communicating at the ends with the chamber B. It has perforations in one wall, and combined with these perforations are valves B⁵, which 105 are held to their seats by springs and by whatever pressure there may be within the chamber, but which open under the influence of the atmosphere outside of the chamber whenever the pressure within the chamber shall be 110 reduced below atmospheric pressure.

I is a stop-cock for admitting a quantity of air to one of the chambers B. When the cylinder is sufficiently charged, this stop-cock should be closed. It is here shown as attached to one of the injectors.

It is the design of the engine herein described to utilize the direct explosion-pressure within one chamber to force the gas or other fuel into another chamber to mix and vaporize the fuel, and to produce a succession of explosions in the several chambers by using piping and igniting devices such as shown, thus dispensing with moving parts, as heretofore employed. This series or succession of 120 explosions may be illustrated as follows: Air is first admitted by means of the stop-cock I, as before explained, to the chamber B 1 and the fluid vapor is mixed therewith. The electrodes are then opened, which causes a spark 125 to ignite the hydrocarbon, causing an explosion which operates upon the water, through the medium of the valves, to move the vessel 130 in the desired direction and forces the fuel

through the pipe D' into the chamber B 3 through its injector, where an explosion is occasioned by parting the electrodes therein by means of the connection h² with the piston 5 H', connected to the chamber B 1, which is allowed to fall of its own weight by the vacuum created in said chamber B 1 by the initial explosion. This vacuum also operates the valves B⁵ within the inlet B⁴, thus admitting atmospheric air to the chamber for the following explosion in said chamber. The same operation takes place in the several chambers successively, and they are so connected by the pipes D' that when an explosion takes place 10 in the chamber near the port side of the vessel the next explosion takes place near the starboard, and back and forth, so that the vessel will not be turned from her course. 15

The present illustrations show the course of the explosion to be from B 1 to B 3, thence to 20 B 2, thence to B 4, and thence to the starting-point B 1.

It is obvious that the intense heat generated by the explosion will in the case of liquid fuel assist its vaporization by the injector 25 E, and thus aid the rapidity and completeness of the explosions.

Having described my invention, what I claim is—

30 1. In an engine, the combination of a num-

ber of combustion-chambers, pipes or conduits conveying the product of combustion from one chamber to another, an apparatus for igniting the contents of the chambers, and motors for operating said igniting apparatus, 35 substantially as specified.

2. In an engine, the combination of two or more combustion-chambers, said chambers having communication by means of conduits, feed-injectors for said chambers communicating with said pipes, a receptacle for hydrocarbon connecting with the chambers, and an apparatus for igniting the contents of the chambers in succession, substantially as specified. 40

45 3. In an engine, the combination, with a combustion-chamber and an igniting apparatus, of the piston-valve operating in a cylinder on the chamber and having connection with an igniting device, substantially as specified. 50

4. In an engine, the combination of a number of combustion-chambers, fuel-feeders therefor, and igniting apparatus, the fuel-feeder belonging to one combustion-chamber being in communication with a different combustion-chamber, substantially as specified. 55
